UNITED STATES PATENT OFFICE.

ROBERT EDWIN REARDON, OF WASHINGTON, DISTRICT OF COLUMBIA.

HOLDER FOR EXPLOSIVE TARGETS.

Original application filed March 13, 1917, Serial No. 154,563. Divided and this application filed May 29, 1920. Serial No. 385,296.

To all whom it may concern:

Be it known that I, ROBERT EDWIN REARDON, a subject of the King of Great Britain, residing in the city of Washington, in the 5 District of Columbia, United States of America, have invented a new and useful Improvement in Holders for Explosive Targets, of which the following is a specification.

10 This invention is a subdivision of the subject of my United States patent application filed March 13, 1917, Serial No. 154,563, on which Patent No. 1,321,849 issued November 18, 1919, for new and useful improvements 15 in explosive targets, and relates to holders for targets that indicate by audible means when a bull's eye hit is made. The object of this invention is to furnish for such targets a target holder which will hold them 20 conveniently for use and provide means for the ready replacement of the hit indicating means after a hit thereon. A special object of this invention is to provide a hand or 25 automatically adjusted target and holder for realistic rapid fire rifle practice with the device known as the target practice rod, wherein an extensible rod is mounted in a gun barrel, adapting it for miniature target practice without the use of ammunition; each perfect 30 shot in this case being indicated by an explosion in the target.

With the objects in view, the invention consists in the construction, combination and arrangement of parts hereinafter described 35 and particularly pointed out in the claims, it being understood that I do not intend to limit myself to the details of construction of the various parts.

The invention is illustrated in the accompanying drawings in which—

Figure 1 shows a front elevation of one form of this invention.

Figure 2 shows a front elevation of another form.

Figure 3 shows a front elevation of the device of Fig. 2 with the pivoted front cover turned down.

Figure 4 shows a vertical central sectional view of the device of Fig. 2.

Figure 5 shows a paper disk forming a part of the device of Fig. 2.

Figure 6 shows a front elevation of still another form of this invention.

Figure 7 shows a vertical sectional view 55 of the device of Figure 6.

Figure 8 shows a front elevation of a carrier or holder for any or all of the devices of Figs. 1 to 7.

Figure 9 shows a modified detail.

In the drawings, the numeral 11 indicates 60 a block formed of any suitable material forming a carrier for the target proper and its operating mechanism. This block houses in its upper part, a spool 12, removably journaled on a pin 13. This spool carries a 65 strip of paper or tape 14 wound upon it, which tape has provided upon it a plurality of targets having bull's eyes 15 and 15. These bull's eyes are either composed of or carry explosive disks or caps. The tape 14 70 passes from the roll through a slot 17 in the front face of the carrier 11 down over the front face to the bottom of the carrier where it passes through another slot 18. Under the front face at the bottom of the carrier, 75 is provided a resilient roller 19 operated manually by means of a knurled head 20, which roller frictionally engages the tape 14 so that operation thereof moves the tape downwardly, unwinds it from the spool and 80 re-positions new targets. 21 represents mechanisms for limiting rotation of the roller 19 to one direction. An edge 23 is provided whereby the used targets may be torn from the strip of good ones. 24 indicated 85 means for hanging up the carrier 11.

In the modified form shown in Figs. 2 to 5, 11^a represents a carrier corresponding to the carrier 11 in Fig. 1. This carrier is provided with a front face 25, pivoted at 90 26, so that it may be turned down, as shown in Fig. 3. The front face 25 carries a target 27 of the type used for bull's eyes 28 and 29 thereon, one that is aimed at and the other which is actually hit. This target is mov- 95 ably held by the bar 30. Back of the front face, the carrier 11^a has journaled in it, a metal disk 31, carrying a square pin 32 and having near its periphery, a series of apertures 33, which are larger on the back of 100 the plate than on the front. 34 represents a spring back of the plate acting upon it to cause its rotation. 35 indicates a finger carried by the plate, adapted to engage a stopping pin 36 on the carrier. Means for permitting the plate to rotate step by step are provided in a plunger 37, having a round head for engagement with the apertures 33. This plunger is acted upon by a spring 38, carried in the back of the carrier 11^a. 39 110

indicates a paper disk carrying a series of explosive caps 40, positioned to register with the apertures 33 when the disk 39 is applied to the plate 31, as indicated in Fig. 4. The 5 square opening 41, in the paper disk, fits upon the square pin 32 of the plate 31 to cause this registering without any difficulty. In Figs. 6 and 7, 11^b indicates a carrier equivalent to the carriers 11, and 11^a, previously described. The upper part houses a spool 43, removably journaled on a pin 44 and adapted to carry a tape 45, having a plurality of explosive disks or caps 46 placed along its center line. 47 indicates perforations carried by the tape 45. The tape passes from the spool downwardly through a passage way, extending longitudinally of the carrier 11^b and just in front of its rear face. 49 indicates a plunger or firing pin extending from the front face of the carrier inwardly to set off or fire the caps 46 as they pass before it. Movement inwardly of this pin 49 moves the arm 51 rigidly attached thereto at 50, which arm engages the teeth 52 and rotates roller 53 step by step. This roller carries pins 54 adapted to engage perforations 47 of the tape, so that it is moved a step at a time whereby a new cap is fed to exploding position in front of the pin 49 as soon as the previous one has been fired. The carrier 11^b is adapted to receive a paper target 55 in all respects similar to the target 27 in Fig. 2. The target will be so placed that the bull's eye actually hit will be placed 35 immediately over the firing pin 49.

As the target should be approximately in the plane of the shooter's eye, it will be understood that its height must be changed to suit different individuals and to render 40 this easy, a device is provided that is shown in Fig. 8. It consists of a back 65 of any suitable material but preferably light metal having its lateral edges 66 curved around upon themselves, which edges are adapted 45 to engage any of the devices of Figs. 1, 2 and 6 by the provision of grooves 67 in their sides for the edges 66 to engage. 68 represents means for suspending the holder upon the wall. The edges 66 frictionally engage 50 the grooves 67 of the carriers so that they may be readily adjusted vertically to the desired height.

In Fig. 9, a slight modification is shown in which, instead of placing the explosive caps 55 on the paper targets, a projection 60 is provided on the bull's eye to be hit on the usual paper target 61 and the explosive cap 62 is placed in a holder 63, carried by the target practice rod 64 of the gun.

60 The operation of the invention is as follows: In Fig. 1, the target is shot at and if

a bull's eye hit is made, the cap or disk located at or forming the bull's eye is exploded so the shooter knows of the perfect shot. Upon the explosion of a disk, the shooter 65 turns the head 20 which causes the unwinding of the spool carrying the tape formed of targets and brings a new one into shooting position.

In Figs. 2 to 5, if the shooter hits the 70 bull's eye, a cap is exploded in the same manner. However, the impact causing the explosion of the cap will cause the momentary retraction of the spring pressed plunger 37, which retraction from the aperture in the plate 31 that it engaged will permit the spring 34 to rotate the plate 31 and paper disk 39. The plunger 37 will return to normal position at once because of the spring 38 and will engage the next aperture 75 33 as it comes around and thereby stop the plate 31 and paper disk 39 with a new explosive cap in bull's eye position ready for another shot from the gun. This automatic action continues until all the caps have been exploded. Then the shooter must put a new paper disk upon the plate 31 and give the plate one rotation to rewind the spring 80 34 when the device is ready for use again.

In the device of Figs. 6 and 7, the impact 85 of a bull's eye hit depresses the plunger or firing pin 49 and the cap opposite it is exploded. Movement of the pin 49 is transmitted through its associated mechanism to rotate the roller 53 one step which in turn 90 removes the exploded cap from opposite the plunger 49 and replaces it with a new one by movement of the tape 45 carrying the caps a step at a time. This feed is automatic 95 until all the tape on the spool 43 has been used whereupon it must be replaced with new by the shooter.

What I claim is:—

1. In a holder for targets, an aiming point, a percussion anvil, and means for traversing sound productive material across said percussion anvil. 105

2. In a holder for explosive targets, an aiming point, a hit recording point, and means for automatically traversing explosive units across said hit recording point. 110

3. In a holder for explosive targets, an aiming point, a hit recording point, and hit actuated means for automatically stepping explosive units across said hit recording point. 115

4. In a holder for explosive targets, an aiming point, a hit recording point, and spring means for automatically stepping explosive units across said hit recording point. 120

ROBERT EDWIN REARDON.
